UNITED STATES PATENT OFFICE.

CHARLES J. NELSON AND OLAF OSTLIN, OF MAYWOOD, ILLINOIS, ASSIGNEES TO AMERICAN
CAN COMPANY, OF NEW YORK, N. Y., A CORPORATION OF NEW JERSEY.

DOUBLE SEAMING MACHINE.

No. 923,688.

Specification of Letters Patent.

Patented June 1, 1909.

Application filed January 31, 1908. Serial No. 413,538.

To all whom it may concern:

Be it known that we, CHARLES J. NELSON and OLAF OSTLIN, citizens of the United States, residing in Maywood, in the county of Cook and State of Illinois, have invented a new and useful Improvement in Double-Seaming Machines, of which the following is a specification.

Our invention relates to improvements in double seaming machines.

In double seaming machines heretofore in use of the kind wherein the can is chucked by operation of a foot treadle, the depression of the foot treadle serves to set the seaming mechanism in operation and to hold it in operation until the operator relieves the pressure on the foot treadle and permits the can to separate from the upper rotating chuck. This frequently occasions defective work, as it is desirable that the seaming roller should be pressed against the rotating can only for a proper and uniform time.

The object of this invention is to provide a double seaming machine of a simple, efficient and durable construction, in which the operation of the foot treadle in lifting the lower can chuck to chuck the can against the upper rotating chuck, will set the seaming mechanism in operation for a complete cycle only, or for the time necessary for seaming one can, and then automatically throw it out of operation whether the foot treadle be kept depressed or not.

The invention consists in combination with a pair of rotatable can holding chucks and the double seaming tools or rollers, operating mechanism for advancing and holding them against the seaming flanges of the rotating can, a foot lever or treadle for lifting the lower can holding chuck against the upper rotating chuck, connecting mechanism for setting the seaming mechanism in operation when the lower chuck is raised, and a safety trip device operated by the foot treadle in the act of chucking the can, and which acts to automatically stop or disconnect the seaming mechanism as soon as it completes its cycle or period of operation on each can, so that the seaming rollers will be withdrawn from the can at the proper time independent of the action of the operator's foot on the foot treadle.

The invention further consists in combining with the seaming rollers and upper and lower chuck disks, of a yielding support or

cushion for the bearing of the upper chuck disk so that the upper chuck disk will operate to hold the can yieldingly against the pressure or thrust of the seaming tools.

The invention further consists in the novel construction of parts and devices and in the novel combinations of parts and devices herein shown and described, and more particularly specified in the claims.

In the accompanying drawing forming a part of this specification, Figure 1 is a side elevation of a double seaming machine embodying the invention. Fig. 2 is a front elevation. Fig. 3 is a detail section on line 3—3 of Fig. 1. Fig. 4 is a detail section on line 4—4 of Fig. 1. Fig. 5 is a detail section on line 5—5 of Fig. 4. Fig. 6 is a horizontal section on line 6—6 of Fig. 7, and Fig. 7 is a vertical section on line 7—7 of Fig. 6, and Fig. 8 is a detail sectional view showing the clutch. Fig. 9 is a detail sectional view on line 9—9 of Fig. 7 and Fig. 10 is a detail perspective view of the clutch disengaging device.

In the drawing, A represents the frame of the machine.

B is the lower rotatable and reciprocating can holding chuck, having its stud or shaft b furnished with an end pivot or antifriction bearing b¹ supported on a yielding or cushioned plug b² in the reciprocating stem B¹ of the lower chuck, which is furnished with a socket b³ to receive said stud b, the yielding support b² and its spring b⁴. The stem B¹ moves up and down in suitable guides A¹ on the frame of the machine, and is reciprocated as required to chuck the can against the upper rotating chuck C, by means of a foot treadle D connected by an adjustable link d with the lever d¹, which is pivoted to the frame at d² and is connected at its outer end to a clamp d³ which is secured to the reciprocating stem B¹ of the lower chuck a spring d⁵ connected to the treadle D restores it to normal position.

The upper chuck C for the can has its shaft C¹ journaled in a bearing C² which is furnished with a cushion or yielding support C³ in the frame bracket A² so that the upper rotating can chuck and the upper end or head of the can therein may be held with a yielding pressure against the seaming tools or rollers F F¹ as the same are forced against the rotating can between the chucks B C. The upper can chuck C or its shaft C¹ is ro-

tated continuously from the driving shaft E, which is furnished with fast and loose pulleys E¹ E² through the bevel gears E³ E⁴, the latter being on the shaft C¹ of the upper 5 chuck.

C⁵ is an adjusting screw bearing against the upper end of the chuck shaft C¹ for adjusting the position of the upper chuck in respect to the seaming rollers F F¹. The double seaming tools or rollers F F¹ are mounted on independently movable tool holders or slides F² F³, and are reciprocated as required to force them successively one after the other against the seaming flanges x x¹ of the can 10 cover X and can body X¹ as the can is rotated by the rotary can holding chucks B C by means of independently adjustable vibrating levers F⁴ F⁵, each furnished with a hardened steel bearing plug f, engaging a 15 similar hardened steel bearing plug f¹ on the tool holder slide, and also with a roller f² which engages the operating cam g on the cam shaft G.

The seaming tools and their holders or 20 slides F² F³ and their operating levers F⁴ F⁵ and the cam shaft G are all mounted on an adjustable tool carriage or slide H, adapted to be moved in suitable ways A³ on the frame of the machine, to adjust the machine for 25 operation upon cans of different sizes or diameters. The seaming tool operating levers F⁴ F⁵ are adjustably and pivotally connected at their upper ends to the carriage H by connecting blocks f³ and adjusting screws f⁴. 30 The slide or carriage H is adjusted to and from the can holder chucks by means of an adjusting screw H¹. It is fixed rigidly in any particular position to which it may be adjusted by a clamp or set screw h, having a handle 35 h¹. The cam shaft G is intermittently operated or rotated as required from the driving shaft E, preferably by a pulley E³ thereon through a belt E⁴ engaging a pulley K on a shaft K¹ carrying a worm K², which engages 40 a worm gear M on a clutch sleeve M¹ which is loose on the cam shaft G, and which clutch member M¹ is adapted to engage a sliding clutch member M², having a spring m and carried on a sleeve or grooved wheel M³ which 45 is fixed on the cam shaft G. The sliding pin or member M² of the clutch is normally held out of engagement with the toothed clutch member M¹ by the spring m, and is retracted at intervals as required to connect and disconnect the cam shaft from its continuously 50 revolving worm gear by means of a curved or crescent shaped cam N adapted to fit in and engage a notch m² in the clutch pin M², and thus retract the clutch pin from engagement 55 with the clutch member M¹ after the cam shaft makes one complete revolution. The movable clutch operating cam or device N is secured to a sliding stem N¹ having a spring n for holding it normally in the groove 60 m³ of the clutch wheel or sleeve M³. The

stem N¹ is furnished with a notch n² which is adapted to be engaged by a safety trip device P on the operating arm P¹ of the rock shaft P² which has an arm P³ connected by a link P⁴ with the treadle D. The safety trip 70 device P is mounted to slide on the arm P¹ and is furnished with a spring p and with a pin p¹ having a roller p² which engages a stationary cam p³, which operates to retract the safety trip device P immediately after the 75 movable cam or wedge N is withdrawn from the clutch pin by the depression of the treadle D.

The cam shaft G is also furnished with a stop cam G¹ which is fixed to the shaft G, 80 and which is provided with a notch G² which engages a roller R on the bent lever R¹ which is connected by a link R² with the treadle D through the lever d¹. The lever d¹ has a slot d⁴ for connection with the link R² so that the 85 treadle D may partially raise the lower chuck before the locking lever R¹ is disengaged from the stop cam on the rock shaft.

In operation, the can to be seamed is first placed on the lower can holder chuck B and 90 then the operator, with his foot on the treadle D, depresses the treadle and thus raises the lower chuck until the can is clucked against the rotating chuck C and thereby revolved. As the treadle D is depressed, the locking lever R¹ is lifted out of engagement with the stop cam G¹, thus permitting the cam shaft G to rotate. The further depression of the treadle D withdraws the movable crescent wedge or cam N from the clutch pin or member M², and permits the same to engage the toothed clutch member M¹, and thereby 95 clutch the cam shaft to the continuously rotating worm gear M. The slight further depression of the treadle D causes the pin p¹ of 100 the safety trip device P to engage the stationary cam p³ and thus release the stem N¹ of the clutch disengaging device N, and thus permit its spring n to return it to position in the cam groove m³ in the wheel or sleeve M³ 105 so that when the cam shaft G completes its revolution, the sliding clutch pin M² will be disengaged from the toothed clutch member M¹ on the worm gear M, and the further rotation of the cam shaft stopped. 110

We claim:—

1. In a double seaming machine, the combination with a pair of rotary can holding chucks, of means for rotating said chucks, double seaming tools, operating mechanism 120 for advancing and holding them against the seaming flanges of the can and cover, connecting means between said chuck rotating means and said seaming tool operating mechanism, a foot treadle for raising the lower can holding chuck against the upper one, connecting mechanism for setting the seaming mechanism in operation when the lower chuck is raised, and a safety trip device operated by the foot treadle in 125 130

the act of chucking the can, and cam means controlled by said safety trip devices to automatically stop or disconnect the seaming mechanism when the period of operation of each can is completed, substantially as specified.

5 2. In a double seaming machine, the combination with rotary can holding chucks, of means for rotating said chucks, double seaming tools, operating mechanisms for forcing and holding the seaming tools against the can, and a yielding support for the can chuck adjacent to the seaming tools to afford a yielding pressure between the seaming tools and seam, substantially as specified.

10 3. In a double seaming machine, the combination with a pair of rotatable can holding chucks, of means for rotating said chucks, seaming tools, operating mechanisms therefor, connecting means between said chuck rotating means and said seaming tool operating mechanism, a foot treadle for reciprocating the lower can holding chuck, connecting mechanism between said treadle and the seaming tool operating mechanism for setting the same in operation, comprising a movable clutch member, a movable disengaging device therefor, a spring for holding said disengaging device in its normal position, an operating arm for actuating said clutch disengaging device from said foot treadle, and a safety trip device connecting said operating arm with said clutch disengaging device, said safety trip device automatically stopping the seaming mechanism at the completion of each cycle of operation, substantially as specified.

15 4. In a double seaming machine, the combination with a pair of rotary can holding chucks, of means for imparting rotary movement thereto, a pair of double seaming tools, a pair of reciprocating holders for said tools, guides in which said holders reciprocate, a pair of operating cams, and a pair of levers fulcrumed against said tool holders and interposed between said cams and said tool holders, said levers bearing centrally against the tool holders and pressing them in the direction of the seam to prevent binding of the tool holders in their guides and consequent imperfect, unequal and irregular seaming action, substantially as specified.

20 5. In a double seaming machine, the combination with a pair of rotary can holding chucks, of means for imparting rotary movement thereto, a pair of double seaming tools, a pair of reciprocating holders for said tools, guides in which said holders reciprocate, a pair of operating cams, and a pair of levers fulcrumed against said tool holders and interposed between said cams and said tool holders, and adjusting screws for said interposed levers, said levers bearing centrally against the tool holders and pressing them in the direction of the seam to prevent bind-

ing of the tool holders in their guides and consequent imperfect, unequal and irregular seaming action, substantially as specified.

6. In a double seaming machine, the combination with a pair of rotary can holding chucks, of means for imparting rotary movement thereto, a pair of double seaming tools, a pair of reciprocating holders for said tools, guides in which said holders reciprocate, a pair of operating cams, and a pair of levers fulcrumed against said tool holders and interposed between said cams and said tool holders, said tool holders and levers having interengaging hardened bearing plugs, said levers bearing centrally against the tool holders and pressing them in the direction of the seam to prevent binding of the tool holders in their guides and consequent imperfect, unequal and irregular seaming action, substantially as specified.

7. In a double seaming machine, the combination with a pair of rotary can holding chucks, of means for imparting rotary movement thereto, a pair of double seaming tools, a pair of reciprocating holders for said tools, a pair of operating cams, a pair of levers interposed between said cams and said tool holders, and an adjustable carriage upon which said tool holders, cams and levers are mounted, substantially as specified.

8. In a double seaming machine, the combination with a pair of rotary can holding chucks, of means for imparting rotary movement thereto, double seaming tools, operating mechanism for advancing and holding them against the seaming flanges of the can and can cover, connecting means between said chuck rotating means and said seaming tool operating mechanism, a foot treadle for raising the lower can holding chuck against the upper one, connecting mechanism for setting the seaming mechanism in operation when the lower chuck is raised, and a safety trip device operated by the foot treadle in the act of chucking the can to subsequently automatically stop or disconnect the seaming mechanism when the period of operation on each can is completed, a stop cam and a locking device engaging said stop cam, substantially as specified.

9. In a double seaming machine, the combination with a pair of rotary can holding chucks, of seaming tools, operating mechanism therefor, a foot treadle for reciprocating the lower can holding chuck, connecting mechanism between said treadle and the seaming tool operating mechanism for setting the same in operation and disconnecting the same, comprising a movable clutch member, a movable disengaging device therefor, a spring for holding said disengaging device in its normal position, an operating arm for actuating said clutch disengaging device from said foot treadle; and a safety trip device connecting said operating arm with said

clutch disengaging device, and a stop cam and lock device engaging said stop cam, substantially as specified.

10. In a double seaming machine, the combination with an upper can holding chuck, of a lower reciprocating can holding chuck, a foot lever for reciprocating the same, a seaming tool, a cam and cam shaft for operating said seaming tool, mechanism for intermittently rotating said shaft, comprising a clutch, a movable clutch disengaging device, a movable trip device adapted to engage said clutch disengaging device, whereby said clutch disengaging device when operated by 15 said foot lever to set the seaming roller operating mechanism in motion, is, through action of said trip device, restored to position for disengaging the clutch when the seaming cycle or period is completed on each can independent of the position of the foot lever, substantially as specified.

11. In a double seaming machine, the combination with an upper can holding chuck, of a lower reciprocating can holding chuck, a 20 foot lever for reciprocating the same, a seaming tool, a cam and cam shaft for operating said seaming tool, mechanism for intermittently rotating said shaft, comprising a clutch, a movable clutch disengaging device, a 25 movable trip device adapted to engage said clutch disengaging device, whereby said clutch disengaging device when operated by said foot lever to set the seaming roller operating mechanism in motion, is, through action of said trip device, restored to position for disengaging the clutch when the seaming cycle or period is completed on each can independent of the position of the foot lever; a 30 stop cam and a movable lock therefor actuated by the foot lever, substantially as specified.

12. In a seaming machine, the combination with an upper chuck, of a lower movable chuck, a foot lever for operating it, a seaming

45 tool, operating mechanism for the seaming tool comprising a cam, cam shaft, clutch, a worm and worm gear loose on the cam shaft adapted to be connected thereto by said clutch, a clutch disengaging device, a safety trip device for operating said clutch disengaging device and connections for operating the clutch disengaging device through said safety trip device, substantially as specified.

13. In a seaming machine, the combination with an upper chuck, of a lower movable 50 chuck, a foot lever for operating it, a seaming tool, operating mechanism for the seaming tool comprising a cam, cam shaft, clutch, a worm and a worm gear loose on the cam shaft adapted to be connected thereto by 55 said clutch, a clutch disengaging device, a safety trip device for operating said clutch disengaging device, connections for operating the clutch disengaging device through said safety trip device, and a stationary projection 60 for releasing the clutch disengaging device from the safety trip device, substantially as specified.

14. In a seaming machine, the combination with an upper chuck, of a lower movable 65 chuck, a foot lever for operating it, a seaming tool, operating mechanism for the seaming tool comprising a cam, cam shaft, clutch, a worm and worm gear loose on the cam shaft adapted to be connected thereto by 70 said clutch, a clutch disengaging device, a safety trip device for operating said clutch disengaging device through said safety trip device, a stationary projection for releasing the clutch disengaging device from the safety 75 trip device, a stop cam on the cam shaft and a lock engaging the stop cam, substantially as specified.
